UNITED STATES PATENT OFFICE

ALBION KEITH EATON, OF SCARSDALE, NEW YORK, ASSIGNOR TO SHELL EASTERN PETROLEUM PRODUCTS, INC., OF NEW YORK, N. Y., A CORPORATION OF DELAWARE

DESIGN FOR A BOTTLE

Application filed September 18, 1931. Serial No. 41,149. Term of patent 14 years.

To all whom it may concern:

Be it known that I, ALBION KEITH EATON, a citizen of the United States, residing at Scarsdale, in the county of Westchester and State of New York, have invented a new, original, and ornamental Design for a Bottle, of which the following is a specification, reference being had to the accompanying drawings, forming a part thereof.

In the drawings Fig. 1 is a front elevation of the bottle showing the longitudinal raised ribs and embossed shell; and Fig. 2 is a section on the line 2—2 of Fig. 1.

I claim:

The ornamental design for a bottle as shown and described.

ALBION KEITH EATON.
